UNITED STATES PATENT OFFICE

JOHANNES CRONING, OF HAMBURG, GERMANY, ASSIGNOR, BY MESNE ASSIGNMENTS,
TO CROWN LOCK COMPANY, A CORPORATION OF DELAWARE

CYLINDER LOCK WITH ANNULAR GROOVES

Application filed June 8, 1925, Serial No. 34,649, and in Germany September 22, 1924.

The present invention relates to a cylinder lock wherein the moving parts are adapted to be secured against unauthorized use.

Cylinder locks commonly comprise a cylinder (herein called the locking cylinder) carrying pin tumblers, the ends of which are projected beyond the circumference of the cylinder by springs, except when the proper key moves them against the force of the springs, so that their ends correspond with the circumference of the cylinder, permitting it to be turned within the hollow (herein called the lock cylinder) which carries it. In the conventional standard cylinder lock structure, the pin tumblers are in two parts, one part carried by the locking cylinder with the keyway beneath and communicating with it, and the other carried by the surrounding cylinder, or lock cylinder, with the spring above it. In all cylinder locks, so far as known, holes to receive the pins, or a portion thereof, have been provided in the surrounding cylinder. It is an object of the present invention to reduce the cost of cylinder locks by eliminating the difficulties and expenses connected with the manufacture and assembly of locks having holes in the hollow cylinder receiving or containing the pins or a part thereof. As it is very tedious and inconvenient, especially in winter with cold hands, when inserting the locking cylinder, to manipulate this until the locking pins and holes are opposite one another and as on the other hand the production of the holes is very difficult, according to the present invention the locking pins are received in annular grooves or recesses in the surrounding cylinder so that the key can be withdrawn from the inserted locking cylinder in any position thereof.

An example of construction according to the invention is illustrated in the drawings.

Fig. 1 is a sectional view through the lock assembly including the lock and locking cylinders;

Fig. 2 is an enlarged elevational view of the locking cylinder with a key inserted therein, the tumblers being shown in retracted position;

Fig. 3 is a view similar to Fig. 2, with the

tumblers projected and the key removed; and Fig. 4 is a transverse sectional view on the line 4—4 of Fig. 2.

When the proper key is inserted in the locking cylinder, the ends of the pins correspond with the circumference of that cylinder, so that the locking cylinder *a* can be withdrawn from the lock cylinder *b*, withdrawing the projection *c* from the shaft and thus unlocking it. The preferred form of locking cylinder shown in the drawings comprises one-piece pins *f* provided with an offset portion *g*, so mounted in the cylinder that the offset portion is engaged on one side by a spring *s* tending to force the end of the pin beyond the circumference of the cylinder, and said offset portion may be engaged on the other side by a key *k* inserted in the keyway of the cylinder and the pin thus moved to a position where the end corresponds with the circumference of the cylinder. The locking cylinder *a* is provided with a cylindrical projection *c* for locking a shaft or the like and is guided in a lock cylinder casing *b*. The locking pins *e* engage with annular grooves *d*. The lock cylinder *b* can be screwed or otherwise secured in the casing or the like of the part to be locked or may even form a part of this casing.

The cylinder lock thus constructed with annular recesses in the cylinder or casing surrounding the lock cylinder to receive the ends of the pins when the withdrawal of the key permits the springs to force the ends of the pins beyond the circumference of the cylinder into the annular recesses, is substantially as secure as the cylinder lock wherein the pins extend from holes in both members, and more advantageous for many purposes, because easier to make and assemble and better adapted to accomplish simply and efficiently the locking of sundry parts where the provision of holes to receive the projecting ends of the pins is very difficult.

Having thus described my invention, what I claim is:—

1. In combination with a removable lock cylinder provided with means for retaining tumblers assembled therein so that said tumblers are projectable beyond the circumfer-

ence of the cylinder and withdrawable there-
within by the proper key but inseparable
from the cylinder, a hollow member sur-
rounding said cylinder having annular re-
cesses positioned to receive the projected ends
5 of the tumblers.

2. A locking device comprising a remov-
able locking cylinder containing pin-tum-
blers, springs to move said tumblers so that
10 the ends project beyond the circumference of
the cylinder, means preventing the separation
of said tumblers from the cylinder and a key-
way communicating with the tumblers to
receive a key to move them wholly within the
15 circumference of the cylinder and a hollow
member adapted to receive said cylinder and
provided with annular recesses to receive
projecting ends of the pin-tumblers.

3. A cylinder lock comprising a casing
20 provided with a cylindrical hollow bore hav-
ing annular recesses therein, a removable
lock cylinder mounted in the bore, said cylin-
der being provided with apertures and a key-
way, tumblers mounted in said apertures,
25 means for preventing the separation of the
tumblers from the cylinder when it is re-
moved from the bore, and springs carried
by the cylinder for acting on the tumblers
to project the ends thereof beyond the cir-
cumference of the cylinder and into the re-
cesses in the casing, said tumblers being mov-
able by a key inserted in the keyway in said
cylinder so that the ends of the tumblers
35 are withdrawn from the recesses and within
the circumference of the cylinder.

In testimony whereof I have affixed my
signature.

JOHANNES CRONING.
